GAME APPARATUS

Joseph W. Orcutt, Harry A. Stearns, and Thomas L. Wall, Los Angeles, Calif.

Application January 21, 1935, Serial No. 2,664

9 Claims. (Cl. 273—119)

This invention relates to a game apparatus.

It is an object of this invention to provide an improved game apparatus which is relatively simple and inexpensive in construction and efficient in use.

Another object of the present invention is to provide in a game apparatus, a novel combination of: a cabinet including an inclined playing board; means for propelling balls into the upper portion of said inclined playing board so that they may gravitate thereover; a ball return runway arranged upon said inclined playing board and elevated above the latter for returning played balls toward the lower end of said inclined playing board; a second ball runway arranged upon said inclined playing board including a portion extending below the said first-named or elevated runway and including a reversely curved portion extending above the said first-named or elevated runway adjacent the upper end of the latter; and means arranged adjacent the lower end of the said first-named or elevated runway and below the latter and actuated by a spent or played ball, for reprojecting a spent or played ball toward the upper end of said inclined playing board so that it may enter into the said second-named or lower runway and be deflected by the said reversely curved portion of the latter onto the upper portion of the said first-named or upper runway.

Other objects will appear hereinafter.

The invention consists in the novel combination and arrangement of parts to be hereinafter described and claimed.

The invention will best be understood by reference to the accompanying drawing, showing the preferred form of construction and in which:

Fig. 1 is a plan view of a game apparatus embodying a preferred form of the present invention;

Fig. 2 is a fragmentary perspective view showing a preferred form of the present invention;

Fig. 3 is a vertical sectional view on line 3—3 in Fig. 1;

Fig. 4 is a sectional view on line 4—4 in Fig. 3; and

Fig. 5 is a view, partly in section, showing diagrammatically an electromagnetic circuit embodied in the invention.

A preferred form of the new game apparatus is shown in the drawing, is therein generally indicated at 10, and comprises a cabinet 11 which includes an inclined playing board 12.

Arranged at one side of the inclined playing board 12 is a ramp 13 and arranged at the

lower end of the ramp 13 is a propelling device or plunger 14 by means of which balls may be propelled, one at a time, up the ramp 13 onto the upper portion of the inclined playing board 12 so that they may gravitate thereover toward the lower end of the playing board.

Arranged on the inclined playing board 12 are parallel rails 15 which provide a ball runway 16 and provided in the playing board 12, at the lower end of the runway 16, is an opening 17.

Arranged below the playing board 12 is an electromagnet 18 and pivotally mounted at a suitable point below the playing board 12, as at 19, upon the electromagnet 18, is a ball re-projecting member 20. This member 20 includes a pair of substantially parallel circuit-closing arms 21 and 22, the arm 22 being movable relative to the arm 21 and carrying a contact 23. These circuit-closing members 21 and 22 are arranged in an electromagnetic circuit 24 which includes a source of electrical energy 25, which may be a battery of dry cells or the like arranged in the cabinet 11.

Arranged upon the inclined playing board 12 is an elevated runway 25 which is provided by a pair of spaced rails 26, these rails 26 having downwardly angled end portions 27 which terminate at their lower ends upon the inclined playing board 12 within a confined area 28 there-of, the area 28 being circumscribed by elevated rails 29.

Arranged upon the playing board 12, at the upper end of the runway 25, is a reversely curved ramp or bank board 33 which is provided by a pair of reversely curved rails 30, these rails 30 opening at their lower ends onto the playing board 12, below the elevated runway 25, and extending or projecting over the runway 25 above and parallel to, the upper end portion of the latter, and above the playing board 12.

Mounted upon the playing board 12 adjacent the lower end or mouth 32 of the reversely curved ramp 29—33 is a pair of so-called rebound flags or springs 31 such as are described in our co-pending application, Serial No. 756,102, filed December 5, 1934, upon a Game apparatus.

Operation

A ball propelled by the plunger 14 up the ramp 13 will gravitate over the inclined playing board 12 and, if it enters the open upper end or mouth of the trackway 16 it will gravitate down the latter and engage the relatively movable circuit closing member 22, thereby pivoting the circuit closing member 22 so as to engage the contact 23

carried thereby with the circuit-closing member 21. This engagement of the contact 23 with the member 21 closes the electromagnetic circuit 24 (Fig. 5), thereby energizing the electromagnet 18, 5 whereupon the ball-reprojecting member 20 is attracted by the electromagnet 18 and pivoted (clockwise, from full to dotted line position, Fig. 3). This movement of the ball-reprojecting member 20 projects or propels the ball up the 10 inclined playing board 12, along a path parallel to, but below, the runway 25; whereupon the thus reprojected ball passes between the "flags" or springs 31 into the reversely inclined runway or ramp 33, and the reprojected ball is directed by 15 this ramp 33, onto the runway 25, whereupon it rolls down the runway 25, and down the angled end portions 27 of the latter, into the relatively restricted or confined area 28 of the inclined playing board 12, from which it may pass into 20 any one of the ball exit or scoring openings or pockets 34.

As the reprojected ball passes between the flexible "flags" or springs 31 it spreads the latter apart against the action of their own resiliency 25 (from full to dotted line position, Fig. 1), thereby slowing up or retarding the motion of the reprojected ball so that the latter will not, in all cases, have sufficient momentum left to travel up the reverse ramp 33 onto the elevated runway 25. 30 In the latter event, the reprojected ball will run back down the ramp 33 and engage one of the "rebound flags" or springs 31 and will be deflected by the latter to one lateral side of the ramp 33 and elevated trackway 25, whence the 35 thus deflected ball will gravitate over the inclined playing board 12 toward the lower end of the latter.

While we have illustrated and described the preferred form of construction for carrying our 40 invention into effect, this is capable of variation and modification, without departing from the spirit of the invention. We, therefore, do not wish to be limited to the precise details of construction set forth, but desire to avail ourselves of 45 such variations and modifications as come within the scope of the appended claims.

Having thus described our invention what we claim as new and desire to protect by Letters Patent is:

50 1. In a game apparatus, the combination of: a cabinet including an inclined playing board; means for propelling balls onto the upper portion of said inclined playing board so that they may gravitate thereover; an inclined ball return runway arranged upon said inclined playing board and elevated above the latter for returning played balls to a point adjacent the lower end of said inclined playing board; a second ball runway arranged upon said inclined playing board; said 55 second-named runway including a portion extending below the said first-named or elevated runway and including a portion bent or curved back upon itself and projected above the upper end portion of the said first-named or elevated runway and below the latter; and means, actuated by a spent or played ball, for reprojecting the same over said inclined playing board toward the upper end of the latter so that it may enter into the said second-named or lower runway and 60 be deflected by the said curved portion of the latter onto the upper portion of the said first-named or upper runway.

2. In a game apparatus, the combination of: a cabinet including an inclined playing board; 75 means for propelling balls onto the upper por-

tion of said inclined playing board so that they may gravitate thereover; an inclined ball return runway arranged upon said inclined plane board and elevated above the latter for returning played balls to a point adjacent the lower end of 5 said inclined playing board; a second ball runway arranged upon said inclined playing board; said second-named runway including a portion extending below the said first-named or elevated runway and including a portion bent or curved 10 back upon itself and projected above the upper end portion of the said first-named or elevated runway; and means including an electromagnetic device arranged adjacent the lower end of said first-named or elevated runway and below the 15 latter, and actuated by a spent or played ball, for reprojecting a spent or played ball over said inclined playing board toward the upper end of the latter so that it may enter into the said second-named or lower runway and be deflected by the 20 said curved portion of the latter onto the upper portion of the said first-named or upper runway.

3. In a game apparatus, the combination of: a cabinet including an inclined playing board; means for propelling balls onto the upper portion 25 of said inclined playing board so that they may gravitate thereover; an inclined ball return runway arranged upon said playing board and above the latter for returning balls to a point adjacent the lower end of said inclined playing board; 30 means arranged adjacent the lower end of said runway and actuated by a ball gravitating over said inclined playing board for reprojecting a ball thereover toward the upper end of the same; and means arranged upon said inclined playing 35 board adjacent the upper end of the said runway for reversing the direction of travel of a ball thus reprojected over said inclined playing board by said first-named means and for depositing the same upon the upper or higher portion of said 40 runway.

4. In a game apparatus, the combination of: a cabinet including an inclined playing board; means for propelling balls onto the upper portion 45 of said inclined playing board so that they may gravitate thereover; an inclined ball return runway arranged upon said playing board and above the latter for returning balls to a point adjacent the lower end of said inclined playing board; means arranged adjacent the lower end of said 50 runway and including an electromagnetic device actuated by a ball gravitating over said inclined playing board for reprojecting a ball thereover toward the upper end of the same; and means arranged upon said inclined playing board adjacent the upper end of said runway for reversing the direction of travel of a ball thus reprojected over said inclined playing board by said first-named means and for depositing the same upon 55 the upper or higher portion of said runway. 60

5. In a game apparatus, a cabinet including a member providing a ball-playing surface; a ball runway arranged upon said playing surface above the latter; means arranged adjacent one end of said runway and actuated by a ball traveling over said playing surface for reprojecting a ball thereover; and means arranged upon said playing surface adjacent the other end of said runway for reversing the direction of travel of a ball thus reprojected over said playing surface 65 and for depositing the same upon said runway.

6. In a game apparatus: a cabinet including a member providing a ball-playing surface; a ball runway arranged upon said playing surface above the latter; means arranged between the ends of 75

5 said runway and actuated by a ball traveling over said playing surface for reprojecting a ball over the latter; and means arranged upon said playing surface adjacent one end of said runway for reversing the direction of travel of a ball thus reprojected over said playing surface and for depositing the same in said runway.

10 7. In a game apparatus: a cabinet including a member providing a ball-playing surface; a ball runway arranged upon said playing surface above the latter; means including an electromagnetic device arranged between the ends of said runway and actuated by a ball traveling over said playing surface for reprojecting a ball over the latter; and means arranged upon said playing surface adjacent one end of said runway for reversing the direction of travel of a ball thus reprojected over said playing surface and for depositing the same in said runway.

15 20 8. In a game apparatus, a cabinet including a member providing a ball-playing surface; a ball runway arranged upon said playing surface above the latter; means arranged adjacent one end of

said runway for reprojecting a ball over said playing surface; and means arranged upon said playing surface adjacent the other end of said runway for reversing the direction of travel of a ball thus reprojected over said playing surface 5 and for depositing the same upon said runway.

9. A game comprising a game board having pockets arranged in groups and barriers adjacent said pockets and means for projecting balls over the surface of said board; means for directing a 10 ball toward one group of pockets including a track elevated above the surface of the board and having an end thereof inclined downwardly toward said group of pockets, a return track at the other end of said elevated track to deliver balls 15 upon the latter, a striker movably mounted to re-project a ball over the surface of said board to the return track, and means for actuating said striker.
